J. Nock,

Trunk Lock,

No 65,260.

Patented May 28, 1867.

Inventor:
Joseph Nock

United States Patent Office.

JOSEPH NOCK, OF WASHINGTON, DISTRICT OF COLUMBIA.

Letters Patent No. 65,260, dated May 28, 1867.

IMPROVEMENT IN TRUNK-LOCKS.

The Schedule referred to in these Letters Patent and making part of the same.

TO ALL WHOM IT MAY CONCERN:

Be it known that I, JOSEPH NOCK, of the city of Washington, in the District of Columbia, have invented new and useful improvements in Trunk and Chest-Locks; and I do hereby declare the following to be a full and exact description of the same, reference being had to the drawings that accompany and form a part of these specifications, in which—

Figure I, view of the lock from the front.

Figure II, view of the hasp, looking at the under side thereof.

Figure III, plan view of interior, showing position of parts when the bolt is thrown back so as to withdraw the hasp.

Figure IV, view of the same parts, with the bolt thrown forward as when the trunk is locked.

Figure V, sectional view, showing manner of combining the bolt with the actuating lever.

Figure VI, of hasp with hooks bevelled so as to make it self-locking.

Letter A, lock-plate; letter B, hasp; letter C, hasp-plate; letter D, bolt; letter E, crooked lever, acting in combination with the tumblers F and the bolt D; letter F, series of tumblers; letter g, key; letter h, pin, on to which the hooks i i of the tumblers F clasp to effect the locking; letters j j, bevelled hooks on the bolt D, so that the hooks r r on the hasp B may slip in place merely by pressing the hasp inwards; letter k, spring to keep the bolt D in place; letters l l, staples on the hasp B, differing from r r in Fig. VI, and requiring the use of the key to lock or move the bolt; letter m, spindle, on which is coiled the spring n.

It will be readily seen by the drawings that my invention applies to two different styles of locks, the one self-locking, and the other not.

My invention consists in the manner of combining and arranging the bolt D, the lever E, and the tumblers F, as also in providing against the injury that so often comes to the hasp of trunk-locks by the use of the spring n.

In the interior of the stile that is not self-locking I do not claim anything as especially new; but the arrangement seen in Figs. III, IV, and V, by which a series of tumblers is made applicable to a self-closing lock for trunks and chests, I consider entirely new.

In Fig. V a portion of the lever E is cut away, that the pin or stop s, which throws the bolt D back when the lever is raised by the key, as in Fig. III, may be seen. The use of a spring for throwing out the hasp is not new. My improvement in this respect consists in the manner of fastening the spindle m in the swell of the hasp-plate C. Fig. II will make this plain. The two ends of this spindle have a flattened surface at O, so that by placing a small block on this flattened side, between the jaws P P, and hammering down these jaws, as seen at the opposite end, the spindle is kept from turning, and the spring n, with one end fastened to the spindle m, the other resting against the hasp B, operates to throw the hasp out whenever the bolt is withdrawn, as seen in Fig. I. The spindle m being wholly embedded in the swell of the hasp and hasp-plate cannot be forced out, as has been the case with other locks of this kind of hasp.

I believe these locks of mine to be more safe than any other trunk-locks in use, and yet they are very simple. It is not necessary for me to enlarge upon the great degree of security these locks afford, for what has been said of my inside trunk-locks for which I am seeking Letters Patent is applicable to these.

What I claim as my invention, and desire to secure by Letters Patent, is—

1. The use of the crooked lever E, or its equivalent, in combination with the tumblers F, more or less in number, and the bolt D, arranged substantially as described and shown.
2. I claim the spindle m with the spring n, when inserted and confined in the hasp, substantially as described and for the purposes set forth.

JOSEPH NOCK.
